UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

CARBON-SHEET-ATTACHING MEANS

Application filed July 14, 1928. Serial No. 292,851.

This invention relates to means for facilitating the adjustment of carbons upon fan-fold or continuous-billing machines. This type of machine has a set of carbon-holding blades mounted in stepped order upon a carrier, a carbon being clamped upon each blade, the carrier itself being operable to shift the carbons rearwardly between the plies of a work-web.

10 The carbon-blades may be detached from the carrier in order to secure the carbons thereto. It is found difficult to square up the carbon on the blade, so that the same may feed properly with the web, and it is troublesome to handle the same, due to the thinness of the paper and to the carbon-coating.

15 The carbons must have their front edges aligned after being placed on the machine, which is usually done by tearing off their leading edges by means of the usual front paper-knife on the fan-fold machine.

To overcome the difficulties in aligning the side and leading edges of the carbons, a feature of the invention provides a separate 20 special table or jig upon which a pack containing the desired number of carbons may be aligned prior to placing them upon the machine. By means of edge gages the pack may be aligned and squared up with respect to the carbon-blades in a predetermined manner upon said table. The blades may be fastened upon the table to squarely overlie the 25 rear portion of the gaged carbons at spaced-off distances to allow different predetermined lengths of carbons to be attached to their respective carbon-blades, so that the leading 30 carbon-edges will register when the blades are mounted upon the machine.

The carbon-sheets are aligned by means of 35 a side edge gage and a leading edge gage, after which a clamp is moved to effective position to hold the carbon-sheets in position upon the table until all of them have been attached to their respective carbon-blades.

40 The table at its rear end is provided with holes corresponding in distance to the holes on the stepped carbon-carrier of the fan-fold machine.

A carbon-blade with its well-known pivot- 45 ed clamp open is placed over the top carbon

and attached at one side to the table, for instance, in the lower set of holes. The top of the carbon is then folded forwardly over the blade, and the clamp is swung to effective position to hold the carbon upon the blade. 55 Hereafter the blade is lifted out of the holes and together with the clamped end of the carbon is swung over and placed nearer the bottom of the table, thereby permitting the next carbon-blade to be placed over the second 60 carbon, and located in the following set of holes, when the operation of attaching the carbon may be repeated. In this preparatory manner each blade is loaded with the appropriate length of carbon so as to compensate for said stepped arrangement of the carbon-blades on the machine. 65

A feature includes the provision of a side edge gage upon said table and of a displaceable rear edge gage. The latter gage, by 70 means of a suitable connection, may be held in operative position at the rear end of the table until the carbon-pack is properly aligned and trued upon the table with respect to the blades. Hereafter said rear edge gage 75 may be displaced or dropped below the working face of the table so as to clear the way for the swingable clamp upon the carbon-blades and for the carbons to be mounted thereon. With the rear edge gage withdrawn, the rear 80 portion of the carbon may be freely manipulated to be folded over the carbon-blade, and the clamp freely swung, as shown.

From the foregoing, it will be noted that the present device furnishes the operator 85 with a set of perfectly aligned carbon-sheets which may be quickly and easily prepared by unskilled help. Such preparation will save the operator's time while reducing to a minimum the interruption of her current work. 90

Other features and advantages will hereinafter appear.

In the accompanying drawings,

Figure 1 shows, in perspective, the carbon-aligning device or jig with a pack of carbons positioned thereon while the movable rear edge gage is in raised effective position. 95

Figure 2 is a rear view taken from Figure 1, showing the rear edge gage in ineffective position below the working face of the table 100

and illustrating the means for shifting said rear edge gage up and down.

Figure 3 is a perspective view, showing the rear edge gage ineffective when the carbons are being successively attached to the well-known carbon-blades of fan-fold typewriters.

Figure 4 is a diagrammatical side view upon parts of the fan-fold machine to illustrate the arrangement of the carbons thereon.

The carbon-aligning device includes a plate or table 10 supported by cylindrical feet 11 at the front, and blocks 12 at the rear. A pack of carbons 13 may be positioned upon the table with the aid of a side edge gage 14 and a rear edge gage 15. The side edge gage is adjustable, according to the width of the carbons, by means of ordinary screw-and-slot connections 16, and carries mounted upon its outer edge a clamp-device 17, which is operative to hold the pack of carbons in gaged positions upon the table. The clamp-device may be effective to hold the left-hand margin of the pack, and may be the one disclosed in the patent to Thieme 1,617,728. The rear edge gage, for purposes hereinafter to appear, may be raised and lowered between effective and ineffective position. It includes a flat bar 18 terminating at the right-hand end in a struck-up angular projection or finger-piece 19, by which said gage may be moved sidewardly in either direction thereof and raised or lowered, respectively, due to the presence of an inclined slot 20 at each end of said bar 18, and shouldered screws 21 coacting with the slots and threaded into the rear part of the blocks 12.

Lateral extensions 22 and 23 of the table 10 furnish the base for attaching the carbon-holding blades, and are provided with paired sets of holes 24, in which a well-known carbon-holding blade 25, by means of pins 26 thereon, may be stacked so as to squarely overlie the rear portions of the carbons.

After a pack, including the desired number of carbons, is gaged and clamped down, as shown in Figure 1, an operator may proceed to attach the carbon-blades to the carbon-ends in a manner most clearly shown in Figure 3. Since the pack is securely held in place by the clamp-device 17, the operator now may lower the rear edge gage, as indicated, below the working face of the table, to clear the way for freely handling the carbon rear ends. Upon the standard carbon-blade 25 is pivoted a carbon-holding clamp 27. When the rear gage is withdrawn, the clamp 27 may be swung without obstruction. A left carbon-blade with its clamp open may be placed over the top carbon and attached at one side to the table in the lower set of holes; the top of the carbon is then folded forwardly over the blade and the clamp 27 moved to effective position to hold the car-

bon creased upon the blade. The blade is then lifted out of the holes and, together with the clamped end of the carbon, swung over and placed nearer the bottom of the table, thereby permitting the next carbon-blade to be placed over the second carbon and attached to the table in the lower right set of holes when the second carbon is folded over the blade and clamped. As now this second blade is lifted from its holes and placed upon the front part of the table, it permits the operation of attaching the carbons to their respective blades to be repeated according to the remaining sets of holes, thus affording the desired variation in lengths of the carbons, with the result that the leading carbon edges are properly lined up and registered after the blades are placed upon the machine. Figure 4 diagrammatically illustrates the novel arrangement of the blades, and the registering front edges of the carbons 13, omitting, however, for the sake of clearness, the work-web proper. 28 indicates the carbon-carriage shown to abut an adjustable rear stop 29 upon usual track-rails 30, the carbon to extend over a guide-bar 31, around a platen 32 and about to enter between a usual web-severing knife 33 and the platen.

Variations may be resorted to within the scope of the invention, and portions of the improvements may be used without others.

Having thus described my invention, I claim:

1. A device for facilitating the proper folding of the rear ends of carbon-sheets over the carbon-blades of fan-fold typewriting machines, said device including, in combination, a table upon which to place carbons for preparatory alignment thereof, edge gages upon said table to position carbons thereon preparatory to attaching the same upon the carbon-blades, and means upon the table for locating carbon-blades thereon to squarely overlie the rear portion of said gaged carbons at predetermined spaced-off distances from the rear thereof, so as to allow different predetermined lengths of carbons to be attached to their respective carbon-blades, for the leading carbon-edges to register when the blades are mounted in usual stepped arrangement upon the machine.

2. A device for facilitating the proper folding of the rear ends of carbon-sheets over the carbon-blades of fan-fold typewriting machines, said device including, in combination, a table upon which to place carbons for preparatory alignment, gaging means upon said table to position carbon-sheets thereon preparatory to attaching the same upon the carbon-blades, means for clamping the carbons down upon the table in gaged position, and means upon the table for locating the carbon-blades thereon, said blades to squarely overlie the rear ends of the gaged

carbons at predetermined spaced-off distances from the rear carbon-edge, so as to allow different predetermined lengths of carbons to be attached to their carbon-blades, for the leading carbon-edges to register when the blades are mounted in usual stepped arrangement upon the machine.

3. A device for facilitating the proper folding of the rear ends of carbon-sheets over the carbon-blades of fan-fold typewriting machines, said device including, in combination, a table upon which to place carbons for preparatory alignment, gaging means upon said table to position carbons thereon preparatory to attaching the same upon the carbon-blades, means for clamping the carbons down upon the table, and means upon the table for locating carbon-blades thereon, said blades to squarely overlie the rear ends of said gaged carbons at predetermined spaced-off distances, said gaging means including a rear edge gage-member movably mounted upon said table and displaceable from effective position to clear the way for free manipulation of the rear carbon-edges.

4. A device for facilitating the proper attachment of the rear ends of carbon-sheets upon the carbon-blades of fan-fold typewriting machines, where the rear end of each carbon is folded squarely over its blade, and where a pivoted clamp upon said blade is swung to hold a creased carbon in position upon its blade, said device including, in combination, a table upon which to place carbons for preparatory alignment, gaging means upon said table to position carbons thereon preparatory to attaching the same upon their carbon-blades, and means upon the table for locating the carbon-blades thereon to squarely overlie the rear ends of said gaged carbons at predetermined spaced-off distances, said gaging means including a rear edge gage-member movably mounted upon said table and displaceable from effective position to expose the rear carbon-edges and to clear the way for free manipulation of said pivoted clamp to be swung out beyond said rear edge when a carbon is being attached.

5. A device for facilitating the proper folding of the rear ends of carbon-sheets over the carbon-blades of fan-fold typewriting machines, said device including, in combination, a table upon which to place carbons for preparatory alignment, gaging means upon said table to position carbons thereon preparatory to attaching the same upon their carbon-blades, clamping means for holding said carbons down upon the table, and means upon the table for locating the carbon-blades thereon, said blades to squarely overlie the rear ends of said gaged carbons at predetermined spaced-off distances, said gaging means including a rear edge gage movably mounted upon said table and displaceable thereon to clear the way for free manipulation of said

carbons, there being a double screw-and-slot connection between the rear edge gage and the table, the slots being inclined so that side-ward shift-movement of the gage in either direction will raise or lower the same respectively, the upper or effective position being determined by a curved extension or kink at one end of each slot within which the co-operating screws may be lodged.

6. A device for facilitating the proper folding of the rear ends of carbon-sheets over the carbon-blades of a fan-fold typewriting machine, said device including, in combination, a table upon which to place a pack of carbons for preparatory alignment, gaging means upon said table to position the carbons thereon preparatory to attaching the same upon their carbon-blades, manually-operable means for clamping the pack down upon said table at the front portion thereof, and means for locating the carbon-blades upon the table, said blades to squarely overlie the rear ends of said gaged carbons at predetermined spaced-off distances from the rear carbon-edge, said clamping means to be held effective until each carbon-blade is individually placed in its seat and loaded with a carbon to be lifted out of its seat again and deposited upon the front part of the table, when the clamping means may be operated to release a complete set of carbons.

7. A device for facilitating the proper folding of the rear ends of carbon-sheets over the carbon-blades of a fan-fold typewriting machine, said device including, in combination, a table upon which to place a pack of carbons for preparatory alignment, a side edge gage mounted upon said table and settable laterally according to the width of the carbons, a displaceable rear edge gage, both gages serving to position the carbons upon the table preparatory to attaching the same upon their carbon-blades, a swingable clamp having a finger-piece and mounted upon said side edge gage and effective to clamp the pack down upon the table, and means for locating the carbon-blades upon the table, said blades to squarely overlie the rear ends of said gaged carbons at predetermined spaced-off distances from the rear carbon edge, said rear edge gage including a bar-like member at one end terminating in a finger-piece whereby to be displaced after the pack is gaged and clamped down upon said table.
